UNITED STATES PATENT OFFICE.

WILLIAM CARLILE WALLACE, OF NEW YORK, N. Y., ASSIGNOR OF ONE-HALF TO
JOSEPH E. GARRABRANT, OF NEW YORK, N. Y.

LOCK MECHANISM FOR SLIDABLE WINDOWS.

Application filed December 1, 1923. Serial No. 677,927.

To all whom it may concern:

Be it known that I, WILLIAM CARLILE WALLACE, a subject of the King of Great Britain, and resident of the borough of 5 Manhattan, in the city, county, and State of New York, have invented certain new and useful Improvements in Lock Mechanism for Slidable Windows, of which the following is a specification.

10 This invention relates to window raising, lowering and locking means, and my improvement is directed to certain simple control mechanism of novel character which is easily manipulable under a moderate amount 15 of force to perform the operations of window opening and closing.

While capable of employment with various types of slidable windows, my invention is particularly adapted for use in conjunction 20 with the windows of motor car doors, with which it is especially desirable that the operation thereof be attended with great ease, and also that the window should stay in any set partly open or closed positions 25 without the application of any locking means other than is comprised in the organism of the operating mechanism.

Briefly expressed, my invention comprises the employment of an articulate member, 30 such as a chain, composed of pivotal links, and operable in straight line movement to both pull a window upwardly or to push it downwardly. I have found that by placing a straight length of link chain in a tube or 35 channel of suitable cross-sectional dimensions for its parallel walls to serve as guides, that the chain will function like a stiff plunger when it is subjected to a pushing effort. Therefore, while the window can be 40 pulled by the chain in one direction, it can also be pushed by the same chain in the other direction.

Further my invention comprehends the 45 employment of a two-part wedge device, operable within the chain containing channel and constituting the means of connection between the chain and window. This wedge device is effective as such to hold the window in a set position, either partly open

or closed, under the influence of gravity 50 provided by the weight of the window.

But the wedge device is of such character as to become released both when the chain is pulled upon to open the window and when the chain is pressed against this wedge device, thereby enabling a pushing action of the chain to move the window downwardly. Hence, the window can be easily opened by 55 pulling upon the chain and can be closed with equal facility by pushing upon the 60 chain.

Tensioning means are also provided by me to take up the slack in the chain and to partially counterbalance the weight of the 65 window.

Other features and advantages of my invention will hereinafter appear.

In the drawings:

Figure 1 is an elevation of a motor car door, viewed from the exterior thereof. 70

Figure 2 is a section on the line 2—2 of Figure 1.

Figure 3 is a section on the line 3—3 of Figure 1.

Figure 4 is an enlarged detail view in 75 elevation, showing the operating chain, the channel therefor, and the tensioning means.

Figure 5 is a detail, side view, partly in section, on a still larger scale, showing the 80 wedge device.

Figure 6 is a section on the line 6—6 of Figure 5 showing the wedging operation influenced by upward pull of the chain.

Figure 7 is a similar view showing the 85 wedge releasing operation influenced by downward push of the chain, and

Figure 8 is a section on the line 8—8 of Figure 5.

In said views, let 1 indicate a motor car door, or other frame for a window 2 which 90 is to be capable of being raised or lowered.

With motor car doors the window 2 is usually a plain sheet of glass that runs in guides 3, 3, and is fixed in a base channel 4. This channel is here shown as provided with 95 a lug 5, that engages a spur 6, extended from the base portion 7 of a wedge member 8, which is slidable in a guide or channel 9.

As is well known the front and rear panels 10 and 11 at the lower part of motor car doors are separated by a space which serves to receive the lowered window, and this 5 space also accommodates the operating mechanism.

A complementary wedge member 12 having a head portion 13 is fitted loosely in channel 9, the head portion 13 lying between 10 the end of wedge member 8, and the terminal portion of a chain 14, which chain is 15 slideable within the guide or channel 9. The wedge elements 8 and 12, at their oppositely inclined meeting surfaces, are provided with a raceway 15, containing balls 16, to lessen 20 the friction between them, and said wedge elements are normally urged into a wedging action within the channel 9 by means of a spring 17, interposed between head portion 13 and the opposed end of wedge member 8. Therefore, when the apparatus is in 25 a state of rest the wedge is expanded into frictional contact with the sides of channel 9, thus providing a lock to hold the window in a set vertical position, either closed or partly open.

The window can not be moved from this set position without recourse first being had 30 to means for releasing the wedge, because downward pressure or vibratory influence, applied directly to the window, will merely have the effect of tightening the wedge and locking it more securely.

The chain 14, movable in channel 9, constitutes the actuating medium for the wedge, as well as serving to transmit the force wherewith the window is raised and lowered. One end of this chain is secured, as at 18, 35 to a fixed frame member 19 and the other end is engaged with the upper portion of wedge element 8. The manner of this engagement, as here shown, is of special character. Thus, the upper portion of wedge element 8 is reduced laterally to provide 40 clearances for the accommodation of side bars 20, 20, of the terminal chain link, respectively between its sides and the sides of channel 9, these side bars being provided with aligned, longitudinal slots 21, 21, which 45 receive the projecting ends of a pin 22, that extends transversely through wedge element 8.

The chain 14 is shown as engaged with a 50 spur wheel 23, carried by a shaft 24, here indicated as journaled in a bearing 25, that is secured to the frame member 19 and located near the upper end of channel 9. A handle 26, attached to shaft 24, enables 55 the spur wheel to be rotated, in either direction, for movement of the chain 14 within channel 9. The slack of the chain is taken up by an idler 27 that is mounted on an arm 28, said arm being pivoted to the 60 frame 19 at 29 and yieldingly extended by 65 a tensional member 30. The tension thus

applied serves also to partly balance the weight of the window.

The operation of my improved window control device is as follows: When the chain 70 14 is drawn upwardly within channel 9, as by rotating spur wheel 23 in one direction, the first effect is the movement of side bars 20 until the lower ends of their slots 21 engage the projecting ends of pin 22, (see Fig. 6) whereupon a continued upward pull of 75 the chain first releases the wedging effect of elements 8 and 12, and then freely lifts the window to the desired partly or fully closed position. When the pulling effort ceases the weight of the window causes the 80 wedge element 8 to re-engage wedge element 12, aided by the wedge spreading influence of spring 17.

In order to lower the window, the spur wheel 23 is rotated in the opposite direction, to impart downward movement to chain 14 in channel 9, the slots 21, in this action, descending over the ends of pin 22, until the lower ends of side bars 31, 31, forming 90 part of the adjacent link, come into contact with the top of wedge portion 13, and by continued downward pressure, compressing spring 17 and releasing the engagement of wedge elements 8 and 12; the continued 95 downward pressure thenceforward necessarily having the effect of lowering the window to the desired degree of opening. When the downward pressure is relieved the wedge lock again becomes effective in the manner 100 before described.

The channel opening is guarded by partly covering plates 32, 32, which leave between them a narrow opening, sufficient in extent for the travel of spur 6.

The chain 14, as confined within the channel 9, is as effective under a pushing effort as a rigid bar would be, and thereby enables me to utilize a single chain length for the 105 dual purpose of pulling a window up and pushing it down.

Variations within the scope and spirit of my invention are equally comprehended by the foregoing disclosure.

I claim:

1. Locking means adapted for use in connection with a slideable window having a guide channel and control means, said locking means comprising a wedge connecting element in said channel between the window and control means, a complementary wedge element in said channel, and spring means to normally expand said wedge elements in the channel, to lock the window in a set position, said wedge elements being contractible to release the window by movement in either direction of the control means.

2. Locking means adapted for use in connection with a slideable window having a guide channel and control means, comprising a two-part wedge device within said

channel, one part of said wedge device having means of connection with the window, and also having means of engagement capable of limited slack movement with the control means, the other part of the wedge device being free within the channel, and spring means to normally extend the parts

of the wedge device to frictionally bind it within the guide channel thereby locking the window in a set position. ¹⁰

Executed at New York this 9th day of November, 1923.

WILLIAM CARLILE WALLACE.
